UNITED STATES PATENT OFFICE.

FREDERICK C. BROCK AND WILLIAM E. ALLISON, OF COLUMBUS, OHIO, ASSIGNORS TO
THE J. P. GORDON COMPANY, OF COLUMBUS, OHIO, A CORPORATION OF OHIO.

AUTOMOBILE-TOP.

1,260,120.

Specification of Letters Patent. Patented Mar. 19, 1918.

Application filed December 2, 1915. Serial No. 64,730.

To all whom it may concern:

Be it known that we, FREDERICK C. BROCK and WILLIAM E. ALLISON, citizens of the United States of America, residing at Columbus, in the county of Franklin and State of Ohio, have invented certain new and useful Improvements in Automobile-Tops, of which the following is a specification.

10 Our invention relates to automobile tops and is particularly applicable to automobiles of the "roadster" type.

The development of the automobile has been accompanied in a measure by the development of its top. At first, the normal buggy top was applied to the roadster type of automobile and was also adapted to the "touring" car by the simple expedient of duplicating the bows. It appeared in time 20 that this buggy top structure, besides being unsightly, possessed a further drawback in that its bows offered an obstruction to entering or leaving the car. The first effort to remedy this defect, consisted in the use 25 of a forward bow manually adjustable to assume an operative position wherein its inner end was raised to dispose the bow substantially at right angles to its adjacent bow. This front bow had to be adjusted 30 manually both in collapsing and elevating the top.

With the advent of the "one-man" top for touring car bodies similar structures have been applied to roadsters, though not generally. The evident purpose of this was the avoidance of the necessity for manual adjustment of the front bow and possibly the improvement of the appearance of the top. Whether or not the appearance is important, 35 the necessity for manual adjustment of this front bow before moving it from one position to the other has been a distinct nuisance. Theoretically the one-man tops for roadsters can be thrown up or down by one 40 lift or push. In practice, this is not the case. On the contrary, the operator must set the joints of each side independently.

Our improvement goes right to the heart 50 of the problem. It recognizes the desirability of supporting the top by a single standard on each side with the resultant improvement in appearances and freedom from obstructions to the entrance of the car. It provides a front bow which does not ob-

struct the car entrance when the top is up 55 and this is accomplished by an adjustable front bow. The point is, however, that the said front bow is automatically adjustable rather than manually. Thus this front bow is parallel with its adjacent bow when the 60 top is collapsed, but it automatically moves, with the raising of the top, into a position substantially at right angles to its adjacent bow. Our improvement goes one step farther 65 in that the rear bow of the top is likewise automatically adjustable in a manner substantially similar to the forward bow.

Our invention goes much farther than this, however, for it embodies such structural features that the adjustment of one 70 bow automatically brings about a corresponding adjustment of its complementary bow, due to an operative connection between the front and rear bows.

A feature of importance in our improvement arises from the manner in which we have utilized the forward bow as a lever to raise the rear bow and in the course of such operation to be acted upon by this rear 75 bow to complete the elevation of the front 80 bow.

A noticeable result of our improved structure arises from the fact that an operator can sit in the car or stand in front or on either side of the car, and with one pull or 85 push raise or lower the top.

The manner in which this is accomplished and the advantageous features of our invention will be brought out in connection with the accompanying drawings wherein 90 similar characters of reference designate corresponding parts, and wherein—

Figure 1 is a side elevation of an automobile of the roadster type with our top applied thereto and with the covering thereof 95 partially broken away to disclose the nature of the frame-work.

Fig. 2 is a detail of this frame-work.

Fig. 3 is a plan view of the frame-work of 100 my top with the covering removed.

Fig. 4 is a side elevation of the structure shown in Fig. 1, with the top collapsed.

In the drawings, the body of the roadster 105 may be designated 1 and is shown provided with supports 2 for the pivotal mounting of standards 3 which are joined together at their upper ends by the bow 4. In our construction of top, this bow and its supporting

standards constitute the main-stay of the top and are supplemented by a forward bow 5 and a rear bow 6, the latter preferably carrying a subordinate bow or cross piece 7.

5 The important thing to note, in the first place, is the position of the bows 5 and 6 both when the top is raised and when it is collapsed. When raised, it will be apparent that only one bow is showing and that is the 10 bow 3—4. Furthermore, there is absolutely no obstruction protruding over the door of the roadster.

The manner in which the bows 5 and 6 are supported on the bow 3—4 is best illustrated 15 in Figs. 1, 2 and 3. The bow 5 is pivotally connected intermediate its length as at 8 by links 9 whose opposite ends are pivoted at 10 near the upper ends of the bows 3—4. There is a stop 11 to limit the upward movement 20 of the inner ends of the bow 5. These inner ends may be pulled downward and forward for collapsing the top by handles 12 connected thereto. The obvious result is that the bow 5, being in the position shown 25 in Fig. 1 may be collapsed by grasping and pulling downward on the handles 12. The inner extremities of this bow 5 travel downwardly and forwardly through the position shown in Fig. 2 and then downwardly and 30 rearwardly into parallelism with the bow 3—4 which has been moved backward into the position of Fig. 4.

The bow 6 is connected to the bow 5 by two external links 13, these links being rigidly mounted on said bow 6. (Note that the links 9 are disposed on and connected to the inside of the bow 5 and the bow 3—4.) These links 13 have a pivotal connection to the bow 5 between the extremities thereof 40 and the points of connection 8 of the links 9. Furthermore, the links 13 are slotted as at 14 to ride upon the pins 15. The connection is such that downward movement of the inner ends of the bow 5 draws the links 13 and consequently the bow 6 downwardly 45 and forwardly and then downwardly and rearwardly until finally the bow 6 is likewise parallel with the standards 3.

Close observation of this collapsing operation 50 will show that upward pressure upon the forward extremity of the bow 5 converts this bow into a lever fulcrumed at 8 and pulling the links 13 and the bow 6 into collapsed relation. As will be pointed out, this leverage 55 action is more important in the raising of the top but it is undeniable that it exists in the lowering operation. Not only does the bow 5 serve as a lever, but after partial collapse, the bow 6 tends to apply its weight to the moving outward of the lower end of the bow 5.

In elevation of the top, the operation is 60 reversed. The top is really a "one-hand" top. The bow 5 may be grasped at its forward end or at other points by the occupant

while still in his seat and a moderate forward and upward pull will cause the links 9 to move outwardly and upwardly while the inner ends of the bow 5 move inwardly and upwardly to proper raised position. It is 70 important to notice that this operation causes the bow 5 to exercise the functions of a lever. This lever is fulcrumed at 8 upon the links 9 and its force is applied to the links 13 so that by the exertion of very little 75 power, these links 13 and their bows 6 are thrown toward raised position. When a dead center is past, the weight of the bow 6 becomes an advantage and tends to snap the 80 top into finally raised position. The framework of the top may be covered by a covering 85 16 and may be secured at its forward end by the element 17.

When the top is in collapsed position we 85 find it desirable to provide a means for preventing rattling or accidental displacement of the parts. The means we have illustrated comprises a loop 18 on each of the side standards 3 and two supplemental L-shaped fingers 19 on the upper side and near the 90 rear ends of the bow 5. The manner of co-operation will be apparent by inspection of Fig. 4.

It is unnecessary to again enumerate the 95 advantageous features of this top but it may be noted that the appearance of the car is much improved by the use of a single vertical standard not supplemented by radiating bows. In addition, the parts of this top are not simply dead weights to be lifted or lowered as in the old form of top. Instead, these parts have not only been made automatically adjustable but they have been given an interconnection which at times converts them into levers and affords undeniable 100 mechanical advantages in manipulation.

Having thus described our invention, what we claim is:

1. An automobile top comprising a central bow, a front bow, a rear bow, a link extending from said central bow to an intermediate point on said front bow, said rear bow having a pin and slot connection with said central bow and pivoted to said front bow.

2. An automobile top comprising a central bow, a rear bow having a pin and slot mounting on said central bow, and a front bow linked to said central bow and so connected to said rear bow as to exert a leverage 120 thereon to adjust the pin and slot connection to move the rear bow into and out of operative position.

3. An automobile top comprising a central bow, a front bow, a link connecting said front bow at a point intermediate its ends to said central bow, a rear bow mounted on said central bow and slidable transversely thereof, said rear bow being connected to said front bow in such a manner that said 130

front bow serves as a lever to effect sliding of said rear bow into and out of operative position.

4. An automobile top comprising a main bow, a front bow linked to said main bow and having its inner end adapted to slide along said main bow, and a rear bow directly supported intermediate its ends upon said

main bow by a sliding connection, the inner end of said rear bow being connected to 10 said front bow.

In testimony whereof we hereby affix our signatures.

FREDERICK C. BROCK.
WILLIAM E. ALLISON.
